United States Patent Office.

JOSEPH DOUGLASS, OF McCONNELLSTOWN, PENNSYLVANIA.

Letters Patent No. 71,719, dated December 3, 1867.

IMPROVEMENT IN YARD-MEASURES.

The Schedule referred to in these Letters Patent and making part of the same.

TO ALL WHOM IT MAY CONCERN:

Be it known that I, JOSEPH DOUGLASS, of McConnellstown, in the county of Huntingdon, and State of Pennsylvania, have invented a new and improved Yard-Measure; and I do hereby declare the following to be a full and exact description of the same, reference being had to the accompanying drawings, which are made part of this specification, and in which the figure is a perspective view.

This yard-stick has a handle at one end, and two projecting flanges, which mark the terminations of the measure, which may be a yard, a foot, or other distance within the reach of the expanded arms.

In the drawings, A is the yard-measure, having a handle, B, and flanges C C', at the terminations of the graduated portion.

The right hand grasping the handle, and the thumb of that hand resting on the flange C, the edge of the goods is stretched between flange C and flange C', whereon the thumb of the left hand rests. The thumb and finger now grasp the goods at this point, C', and carry it forward to the flange C, deposit under the thumb of the right hand, and measure another length, as before.

The handle is comfortably grasped by the right hand, without releasing it, at any time, in the process of measuring, and is much better than the yard-stick commonly in use; while the flanges C C' afford more definite means of measurement than the end of the stick manipulated by the thumbs, and capable of variation in either direction at the pleasure or by the carelessness of the measurer.

Having described my invention, what I claim as new, and desire to secure by Letters Patent, is—

The yard-stick, with handle B and measuring-flanges C C', substantially as described.

JOSEPH DOUGLASS.
